CLAIM

The ornamental design for an arm and base for vehicle mirror, as shown and described.

DESCRIPTION

FIG. 1 is a perspective view taken generally from the upper, front, left-hand side of the arm and base for vehicle mirror of the present invention;

FIG. 2 is a front elevational view thereof, the back elevational view being a mirror image of the front elevational view and thus not shown;

FIG. 3 is a side elevational view of the left side thereof; FIG. 4 is a side elevational view of the right side thereof; FIG. 5 is a top plan view thereof; and, FIG. 6 is a bottom plan view thereof.

The broken lines showing the vehicle mirror is provided for the purpose of illustrating environmental structure and forms no part of the claimed design. All other broken lines in the drawings illustrate portions of the article, or the arm and base for vehicle mirror, that forms no part of the claimed design.

1 Claim, 6 Drawing Sheets
